UNITED STATES PATENT OFFICE.

JOHN C. HURLEY, OF NEWARK, NEW JERSEY.

MACHINE FOR COMPUTING WAGES.

Application filed February 10, 1926. Serial No. 87,210.

This invention relates to an improved machine for computing the wages that are calculated from times of arrival and departure as stamped on a workman's time card by the 5 usual form of time clock.

It is well-known that in many places the workmen leave and return sometimes many times during the day and the hands receive various rates of pay so that considerable 10 reckoning is necessary by the person who is to make up the pay roll.

To save time and labor, I have devised this machine by means of which not only can the amounts for full time at various 15 rates of pay be arrived at, but rapid deductions can be made for time to be subtracted from the normal working hours, and when such subtraction of time is accomplished the total pay for the time remaining, that is, the 20 time for which wages is to be paid is indicated and also the total amount of pay due the workmen for such times of employment.

The machine comprises a movable member on which is arranged in the form of a 25 table, the hours of employment within reasonable limitations, and adjacent thereto, complementary numbers indicating the differences between the elapsed time and the full time, also the total rate of pay for said 30 actual working time at various rates of pay per hour. The machine is preferably constructed with an opening and conceals practically everything except the information desired so that the amount can be quickly 35 found.

The machine is preferably constructed so that it can be rapidly manipulated when desired so that if one end of the movable member is to be displaced to reveal matter at the 40 other end, the member can be rapidly moved and at the same time it is mounted so that it can be accurately adjusted from an approximate position. The preferred form 45 comprises a strip or apron secured to two rollers that are parallel so that when it is wound up on one it is unwound from the other.

The invention is illustrated in the accompanying drawings in which Figure 1 is a 50 top view of a machine embodying my invention. Figure 2 is a section on line 2-2 of Figure 1. Figures 3 and 4 are top views of a part of the machine showing the readings when the apron is in various positions.

55 Figure 5 is a face view of a part of the apron or strip.

In the machine as illustrated in the drawings I show a base 10 with a casing 11 on it, the top 12 of the casing being usually inclined for easy observation. Within the 60 casing are placed the movable member and means for manipulating it and I illustrate a strip or curtain 13 which is moved back and forth to place what is to be disclosed under the opening 14 in the top of the 65 casing.

The means illustrated comprises a roller 15 and a roller 16 to which the strip 13 is secured and which is rolled up on one roller and unwound from the other according to 70 the direction of the rotation. The roller 15 is equipped with a handle 17 for its normal movement but rapid movement can be given by the gears 18 and 19, the latter being the larger and having the handle 20 for its 75 manipulation. For reverse movement the spring 20 is utilized as it is secured to the rod 21 which also acts as a brace for the casing and is also secured to the pulley 22 which is connected by a cord 23 with the 80 shaft 24 of the roller 16. It will thus be seen that when the strip is moved forward by the handle 17 and roller 15 the spring is wound up and when the rotation is reversed the spring acts to move the roller 16 and 85 this moves the strip backward. The brake 25 has a handle 26 in a convenient position to allow the strip to run rapidly back when a remote part of the strip is desired for 90 observation.

The casing has affixed thereto a scale 27 graduated in time values which scale is usually detachable and is changed to conform to the hours of daily employment at the plant. In other words it is sub-divided 95 and indicates the duration of the hours of employment per day and the drawing shows a scale of hours from 7:30 a. m. to 4:30 p. m. with three-quarters of an hour interval for lunch. This scale shows one-quarter 100 hour as the minimum division and as only quarter hours are reckoned the scale of the afternoon begins at 1 on the scale as work starts at 12:45. (See a.)

The time scale that is arranged on the face 105 of the strip 13 has a longer range of time sub-division so that it can be used in the machine for hours of employment that require a scale longer than the scale 27 that is illustrated so that the strip need not be re- 110 placed by another.

The machine as it is illustrated relates to

calculating the time for workers paid from 71¢ to 80¢, inclusive, per hour, and greater and less rates of pay can be arranged above and below the rates shown. If the machine 5 is made twice as wide, a shorter strip 13 can be used because the figures of the scale on the strip 13 can be carried over to the left to 61¢ an hour or 51¢ an hour instead of placing them in longitudinal extension on 10 the strip. The columns on the strip 13 that are next adjacent to the scale 27 are arranged to show in the column 28 sub-divisions of time equal to the sub-divisions on the scale 27, in this case 15 minutes running 15 from zero up and in the next column shown at 29 the remainder of the weekly hours of employment.

That is, in the machine as illustrated, the 20 time scale 27 shows sub-divided duration of the daily hours of employment, the column 29 on the scale or strip 13 shows the weekly hours of employment, each succeeding number being reduced by 15 minutes and the 25 complementary number or the time taken out is opposite thereto in the scale 28. In the scale 30 is shown the cents per hour, the weekly wage of which is shown opposite the sub-division of hours in the scale 31, all these providing a convenient wage scale opposite the time scale on the movable member. In order to provide for a more 30 convenient operation of the machine I arrange a pointer or an indicator 32 which has a handle 33, the indicator being usually in the 35 form of a fork so as to bracket the parts of the scale over which it is placed, although a single thin underlining pointer can be used. In operating the machine, the person computing the wages of the men in the plant has 40 the cards that have been stamped by the time clock and as it is now done much arithmetic must be done, particularly when the scale of wages covers a wide field and where many employees leave the plant for short or 45 long intervals.

With this present machine the stack of cards is arranged in handy position and, for example, we will assume that a card is that of a workman making 80¢ an hour and working normally 48 hours a week. If his card shows no time out, he, of course, has worked 48 hours and a glance at the slot in Figure 1 will show in column 29, 48 hours, in column 28, no time out and in column 31, \$38.40 50 which is coming to him for his week's work. We will assume, however, that the card shows that he came to work at 7:30 a. m.; that he went out at 9:15 a. m., that is, sometime between 9:00 and 9:15; returned at 55 1:45 p. m. and worked for the remainder of the day. In this case, the operator would move the pointer 32 down to 9:15, when the workman went out. Then, by means of the handle 17, the strip could be moved so that 60 the scale on the strip 13 would proceed for-

ward until the number opposite 1:45 when he returns is moved up to a position in alignment with the indicator 32.

This operation is shown in Figures 3 and 4, in Figure 3 the pointer being moved down 70 to 9:15 on the scale 27. This is when the workman went out. It will be noted by the operator then that 1:45 is aligned with 5:30 on the scale 28. Then 5:30 is moved up to the pointer 32 and at b in Figure 4 we see at a glance at scale 28 that the workman has lost 3¾ hours. Scale 29 shows that he has, therefore, worked 44½ hours and at 80¢ an hour for this time his week's wage is \$35.40. The rest of the scale shown at 32 comprises 80 columns down to 71¢ per hour so that this workman, if his rate of pay is 79¢ an hour, would have wages of \$34.92 due him, as shown at c, or if he was making 71¢ an hour he would have due him \$31.42 as shown at d. 85

As another example suppose a workman went to work at 7:30 and he left at 9:15 and didn't return that day. The fork can be moved down as shown in Figure 3 to 9:15 and then the number opposite the closing hour 4:30 which is 8:15 as shown at e in Figure 1 is then moved up to the pointer 32 and if this were done there would be noted at the top the visible part of the scale on the strip 13 6:30 as the hours lost 41:30 90 as the hours employed and \$33.04 would appear at the head of column 31 as the week's wage due to him.

Only a fragment of the strip 13 is shown 100 in Figure 5, the strip usually being printed to show rates of pay from 1¢ to \$1 or more an hour by the columns being raised, in series of tens. This arranging of the figures abreast does not cause the use of a strip or 105 apron of undue length.

In using the machine it is usually set for 110 cards of a certain rate and if it were used, say, in a plant employing most of its hands at a rate of from 71¢ to 80¢ an hour, it would be seen from Figure 4 that the rate of pay for a full week is seen through the slit in the cover of the casing, and when deductions are made on a card as described above, the machine is returned to the position shown in Figure 1 and readings made across on the strip until another card appears on which deduction must be made.

If the next batch of cards is for apprentices or the like making, say, 25¢ an hour, the brake 25 is released and the spring 20 carries the strip rapidly back, the brake 25 is then applied when the approximate figures have been arrived at and then, by the handles 17 or 20 the headings of the desired columns are brought under the slit in the cover, the 115 apron being held up close to the top, so as to be easily read, by the idle roller 33.

I claim:

1. In a calculating device, a frame with 120 an opening therein, a movable member in the 125

frame, a scale graduated in time values on the frame, a pointer on the frame adapted for movement over said scale, a time scale on the movable member adapted to position a time graduation at the pointer adjacent a time graduation on the first scale, a wage scale on the movable member adjacent the time scale thereon, means to shift the movable member, whereby upon adjustment of a time graduation on the movable member to a time graduation on the first scale, at the pointer and a further adjustment of the movable member to align a time graduation thereon which is adjacent the time graduation on the first scale equal to the time graduation on the movable member initially set to the pointer, the elapsed time between the time graduations on the first scale and movable member and a corresponding wage value, or a wage value equal to a standard wage less the elapsed time wage value are presented at the opening in the frame.

5 10 15 20 25

frame so as to have its parts successively presented to view in the opening, a scale graduated in time values on the frame, a pointer on the frame adapted for movement over said scale, a time scale on the movable member adapted to position a time graduation at the pointer adjacent a time graduation on the first scale, a wage scale on the movable member adjacent the time scale thereon, means to shift the movable member, whereby upon adjustment of a time graduation on the movable member to a time graduation on the first scale at the pointer and a further adjustment of the movable member to align a time graduation thereon which is adjacent the time graduation on the first scale equal to the time graduation on the movable member initially set to the pointer, the elapsed time between the time graduations on the first scale and movable member and a corresponding wage value, or a wage value equal to a standard wage less the elapsed time wage value are presented at the opening in the frame.

30 35 40 45 50

2. In a calculating device, a frame with an opening therein a movable member in the form of a strip mounted on rollers within the

In testimony whereof I affix my signature.

JOHN C. HURLEY.
